ROTATABLE RACK FOR DATA CONTAINERS OR THE LIKE

Robert L. Patrick, Los Angeles, Calif., assignor to Tab
Products Company, San Francisco, Calif., a corporation
of California

Filed Mar. 24, 1966, Ser. No. 1,622

Term of patent 14 years

(Cl. D33—3)

FIGURE 1 is a perspective view of a rotatable rack for data containers or the like showing my new design, a data container or the like being shown in broken lines;

FIGURE 2 is a fragmentary perspective view thereof, showing a portion thereof in a tilted position;

FIGURE 3 is an enlarged elevation view thereof;

FIGURE 4 is a plan view taken in the direction of line 4—4 in FIGURE 3;

FIGURE 5 is a plan view taken in the direction of line 5—5 in FIGURE 3; and

FIGURE 6 is a plan view taken in the direction of line 6—6 in FIGURE 3.

The broken line showing of a data container or the like is merely for illustrative purposes.

I claim:

The ornamental design for a rotatable rack for data containers or the like, substantially as shown and described.
